OTHER PUBLICATIONS

Exhibit A includes three photographs of a front mounted pull handle for a cabinet drawer, the pull handle and cabinet being manufactured by Shaw Walker under the name Tempo III, one photograph showing a front view of a three-drawer cabinet including pull handles, a second photograph showing a front view of a single drawer including a pull handle, a third photograph showing a side view of the pull handle removed from the drawer (undated).

Primary Examiner—B. J. Bullock

Attorney, Agent, or Firm—Price, Heneveld, Cooper, DeWitt & Litton

[57] CLAIM

The ornamental design for a pull handle, as shown and described.

DESCRIPTION

FIG. 1 is a perspective view of a pull handle showing my new design;

FIG. 2 is a front elevational view;

FIG. 3 is a right-hand side elevation view, wherein the left-hand side elevational view is substantially identical;

FIG. 4 is a top plan view;

FIG. 5 is a bottom plan view;

FIG. 6 is an enlarged sectional view taken in the direction of arrows on line VI—VI in FIG. 2; and,

FIG. 7 is an enlarged fragmentary sectional view taken on line VII—VII of FIG. 2.

FIG. 1

FIG. 2

FIG. 3

FIG. 4

FIG. 5
